DESCRIPTION

FIG. 1 is a perspective view of a tire showing our new tire tread design, it being understood that the tread pattern is repeated uniformly over the outer circumference and shoulder of the tire, the opposite side being the same as that illustrated; and,

FIG. 2 is an enlarged fragmentary front elevation view of the tread pattern of FIG. 1 showing our new tire tread design.

The broken line showing of a tire inner bead and sidewall is for illustrative purposes only and forms no part of the claimed design.
